UNITED STATES PATENT OFFICE.

KURASUKE SAEKI, OF AKASAKA-KU, TOKYO, JAPAN.

RECIPROCATING STRAIGHT-MOTION PUMP.

Application filed April 23, 1921. Serial No. 463,886.

To all whom it may concern:

Be it known that I, KURASUKE SAEKI, a subject of the Emperor of Japan, residing at No. 17 Rokuchome Aoyama Miuamicho, 5 Akasaka-ku, city of Tokyo, Japan, have invented certain new and useful Improvements in Reciprocating Straight-Motion Pumps, of which the following is a specification.

10 The present invention has reference generally to improvements in that class of inventions known as pumps and more particularly relates to hand operated mechanism having a straight line motion.

15 The invention has for its primary object to provide mechanism of the above mentioned character of novel construction which is applicable to the usual hand pumps with a view of minimizing lateral pressure on the pump piston; to reduce wear on the piston and the wall of the pump cylinder and to arrange the parts so as to provide for an easy and effective operation.

20 More particularly the invention consists 25 in the provision of an operating mechanism for pumps having a straight line motion which consists briefly of an auxiliary lever which is arranged substantially vertically of the pump rod and directly connected to the upper end thereof, a side bar or link fulcrumed on the pump frame and pivotally connected to the other end of the auxiliary lever, and a handle pivotally connected with the auxiliary lever substantially medially 30 of the latter, the pivot points of the handle and side bar or link being arranged on the same side of the piston rod.

Other objects as well as the nature, characteristic features and scope of this invention will be more readily apparent from the following description taken in connection with the accompanying drawings and pointed out in the claims forming a part of the invention.

45 The invention is clearly illustrated in the accompanying drawings, in which:

Fig. 1 is a diagrammatic view of the substantial straight line motion forming the present invention, and

50 Fig. 2 is a vertical sectional elevation of a pump to which is applied the improved straight line motion operating mechanism.

Similar characters of reference are employed in all of the above described views to indicate corresponding parts.

Heretofore it has been the custom to oper-

ate hand pumps through the instrumentality of a handle connected to the upper end of the piston or pump rod, the wall of the cylinder of the pump being therefore subjected to heavy lateral pressure especially at the extremities of the stroke. The result has been a deformation of the cylinder bore and wear on the piston and the cylinder, thereby causing a loss of power and a loss of water 65 by leakage.

The present invention consists in the provision of an operating mechanism having an approximate straight line motion so as to eliminate the defects mentioned instant to 70 the use of the other handle.

Prior to explaining the practical application of the invention to a pump, reference will be had to Fig. 1 wherein the principle is diagrammatically illustrated and in which 75 *d* and *e* represent the fulcrums of a handle *A* and an auxiliary lever *B* respectively. The auxiliary lever is pivoted at its free end *a* to a side bar or link *E* to which the handle *A* is connected at *b*, the side-bar being also 80 directly connected to a piston rod *F* at *c*. When the handle *A* is oscillated about the fulcrum *e* to describe an arc of a circle *a*, *a*₁, *a*₂, etc., the auxiliary lever *B* will also describe an arc *b*, *b*₁, *b*₂ etc. at the free end. In 85 other words, when the handle *A* is moved downwardly from the position *b* to the position *b*₁, the auxiliary lever *B* moves from the position *a* to the position *a*₁, while the pivot point *e* assumes the position *c*₁. Continued 90 oscillation of the handle *A* causes the pivot point *c*₁ of the side bar to move to the position *c*₂ and thence to the position *c*₃ etc. so that it will be clear that the positions *c*, *c*₁, *c*₂ etc. successively assumed by the pivot point 95 of the side bar *e* lie in approximate straight line.

With reference to Fig. 2 there is illustrated a pump of the hand operated type including a frame which supports a cylinder *H* in which a piston *G* operates. A rod *F* is connected with the piston and is reciprocated by the improved mechanism one convenient form of which includes a handle *A* fulcrumed to the free end of the pump at *e*. 100 An auxiliary lever *B* is fulcrumed medially of its ends to the inner end of the handle *A* at *b*, one end of the lever *B* being directly pivoted as at *c* to the upper end of the rod *F*. Coacting with the handle *A* and guiding the movement of the lever *B* is a link *E* the respective ends of which are pivotally con-

ected at *d* to the frame and to the opposite end of the lever *B* as at *a*. It will be appreciated in view of the foregoing that upon oscillation of the handle *A* by reason of the substantial vertical position maintained by the auxiliary lever *B* owing to the link *E*, the pump rod *F* is reciprocated while the point of connection *c* of the lever *B* to the rod *F* is maintained in a substantial straight path during the reciprocation as indicated in the dotted lines in Fig. 2, thereby obviating wear and deformation of the piston and cylinder wall of the pump in addition to forming a mechanism which may be easily operated.

It is believed in view of the foregoing that a further detailed description of the operation of the invention is entirely unnecessary. Likewise it is believed that the advantages of the invention will be readily apparent.

Having thus fully described the invention what is claimed as new and desired to be secured by Letters Patent is:

1. Mechanism having approximately straight line motion for reciprocating the

piston rod of a pump including a pivotally mounted handle, a pivotally mounted link and an auxiliary lever fulcrumed to the handle and pivotally connected with the link and the rod of the pump, substantially as 30 and for the purposes set forth.

2. A pump operating mechanism having a straight line motion including in combination, a cylinder, a piston operating therein, a rod connected to the piston, a pivotally mounted handle, an auxiliary lever arranged substantially vertically and fulcrumed medially of its ends to the handle and pivoted at one end to the rod, a pivotally mounted link having its outer end pivotally connected to the opposite end of the auxiliary lever, and the pivot points of the handle and the link being on the same side of the rod, substantially as and for the purposes set forth.

In testimony whereof he affixes his signature.
